UNITED STATES PATENT OFFICE.

WILLIAM EDGAR CLAYTON, OF ALTOONA, KANSAS.

PRIMING ROD.

1,408,443.

Specification of Letters Patent. Patented Mar. 7, 1922.

Application filed December 18, 1920. Serial No. 430,356.

To all whom it may concern:

Be it known that I, WILLIAM E. CLAYTON, a citizen of the United States, residing at Altoona, in the county of Wilson and State 5 of Kansas, have invented new and useful Improvements in Priming Rods, of which the following is a specification.

This invention relates to improvements in priming devices for internal combustion engines and has for an object the provision of 10 means whereby the air may be temporarily cut off from the carbureter for the purpose of enriching the mixture to facilitate starting.

In the majority of carbureters and especially those used upon "Ford" automobile engines, the spring which holds the shutter of 15 the air valve open is so located as to render it exceedingly difficult to replace in the event of breakage or loss of tension and therefore requires considerable time and expense 20 when it is necessary to repair the carbureter in this connection.

The present invention aims to overcome this disadvantage by placing the spring in 25 a position where it may be readily accessible and at the same time increase its efficiency.

Other objects and advantages of the invention will appear as the following description is read in connection with the accompanying 30 drawings, in which the figure shown represents an elevation of a carbureter with the invention applied thereto.

Referring specifically to the drawings, wherein like characters of reference denote 35 corresponding parts, the carbureter which may be of any desired type is indicated at 10, while the stem of the air intake valve or shutter is shown at 11, the latter being equipped with the usual arm 12, to which is 40 ordinarily secured a priming rod. This rod may extend over to the dash of the automobile so as to be within convenient reach when the driver is seated at the wheel, or may extend forward to the front of the hood so as 45 to permit the engine to be primed when the latter is manually cranked.

The present invention is capable of use in

either position and includes a priming rod 13 which may extend over to the dash or to the forward part of the hood, where it may 50 be provided with a suitable operating knob or handle. Formed within the length of the rod 13 is an eye 14, while preferably surrounding the rod is a coiled spring 15; one end of this spring is secured to the eye 14, 55 while the opposite end is secured to a convenient portion of the carbureter. This spring is designed to take the place of the usual air valve spring so as to normally hold the air valve or shutter open to admit 60 air to the mixing chamber of the carbureter in the usual manner. These springs as heretofore constructed were subjected to considerable strain, in that they were of relatively small size, so that they 65 frequently became broken or weak, so that in order to have the carbureter properly function they must be replaced. This was a difficult and tedious operation, so that the 70 time and expense necessary for the replacing of this spring was unduly increased. By arranging the spring in the manner shown and described, the latter may be quickly and easily replaced and in addition, the use of a spring of sufficient size and resiliency is permitted, so that liability of breakage or loss of 75 tension is materially reduced.

The invention is susceptible of various changes in its form, proportions and minor details of construction and the right is here- 80 in reserved to make such changes as properly fall within the scope of the appended claim.

Having described the invention what is 85 claimed is:

In a carbureter, an air inlet, a valve for controlling the same, an operating rod for the valve, an eye formed in the rod and a spring surrounding the rod and having one end secured to the eye and its opposite end 90 secured to the carbureter for holding the valve in open position.

In testimony whereof I affix my signature.

WILLIAM EDGAR CLAYTON.
